UNITED STATES PATENT OFFICE

158,605

PLUMBER'S ROTARY SNAKE TOOL

Leslie J. Marx, Cleveland, Ohio

Application March 17, 1948, Serial No. 145,177

Term of patent 14 years

(Cl. D9—6)

To all whom it may concern:

Be it known that I, Leslie J. Marx, a citizen of the United States, residing at Cleveland, county of Cuyahoga, and State of Ohio, have invented a new, original, and ornamental Design for Plumber's Rotary Snake Tool, of which the following is a specification, reference being had to the accompanying drawing, forming a part hereof.

Fig. 1 is a view in elevation of the front of a plumber's rotary snake tool, showing my novel design.

Fig. 2 is a view in elevation of the rotary snake tool as seen from the right side of Fig. 1.

Fig. 3 is a view in elevation of the back of the rotary snake tool.

Fig. 4 is a top plan view of the rotary snake tool.

The dominant features of my design reside in these portions shown in full lines.

I claim:

The ornamental design for a plumber's rotary snake tool, substantially as shown and described.

LESLIE J. MARX.
